UNITED STATES PATENT OFFICE.

ISABELLA VREELAND, OF PATERSON, NEW JERSEY, ADMINISTRATRIX OF
ANTHONY W. O'BLENUS, DECEASED.

COMBINED COT AND CRIB.

No. 828,001.

Specification of Letters Patent.

Patented Aug. 7, 1906.

Application filed April 23, 1904. Serial No. 204,504.

To all whom it may concern:

Be it known that I, ISABELLA VREELAND, of Paterson, Passaic county, New Jersey, am the administratrix of the estate of ANTHONY W. O'BLENUS, late of River Edge, Bergen county, New Jersey, who did invent certain new and useful Improvements in a Combined Cot and Crib, of which the following is a specification.

10 The invention relates to a combined cot and crib having among its objects convenience and durability.

Another object is to provide a folding combined cot and crib which may be readily converted into a cot or into a crib, as desired, the parts being adapted to fold together when the device is to be stored or transported.

20 The invention consists of certain novel features and combination of parts to be herein-after described and then claimed.

In the accompanying drawings, which show a suitable form of combined cot and crib of which, for example, the invention is 25 susceptible, Figure 1 is a front view of the improved combined cot and crib. Fig. 2 is an end view thereof. In both of these figures the rockers are shown as out of use. Fig. 3 is an end elevation of the folded device. 30 Fig. 4 is a detail view showing how the canopy is secured to one side of the cot-frame, and Fig. 5 is a detail view of parts of the frame.

The cot-frame comprises a rod *a*, at one end 35 of which are pivoted two crossed bars, legs, or supports *b c* and at the other end two similar crossed bars *d e*. The upper ends of the legs *b d* are connected by a side bar *f* and the upper ends of the legs *c e* by a side bar *f'*, parallel with the side bar *f*, the said side bar, being connected by a web *g*, of suitable fabric, 40 forming a bottom. At opposite sides of preferably the mid-length of the rod *a* are sockets *g' g''*, in which may be inserted the lower ends of braces *h h'*, the upper ends of 45 which support the middle portions of the side bars *f f'*. The described parts constitute a cot.

Pivotedly mounted at *i* on the lower ends 50 of two opposite legs—as, for instance, the legs *b d*—are rockers *j j'*, such pivotal connection being near one end of each rocker. In such case the other legs *c e* are provided at their lower ends with abutments or stops, such as

k, with which the inner edges of the free ends of the rockers are engaged when the device is employed as a crib and against which they are held by suitable means, preferably by a rope or cord *l*, one end of which is secured to an eye *m* on one of the rockers, as *j'*, while the other end passes through eyes *l' l''* on the legs *d b* and through an eye *m* on the other rocker. The free end of the cord or rope may be secured to a hook or eye *m'* on leg *b*. When the rope or cord is trained, as stated, drawn 65 taut, and tied fast, the rockers may be held firmly against the stops and the cot becomes a crib. A stay-rope *n* connects one of the legs, as *d*, with its crossed leg, as *e*, the stay-rope being connected to eyes, such as *t* and *u*, 70 in the respective legs.

The cot or crib is provided, preferably, with a canopy which comprises a rectangular frame *o*, connected at one edge by hinges *o'* with the side bar *f'*, together with another 75 similar frame *p*, connected at one edge with the other edge of the frame *o* by means of links *p'*. The frames *o p* are of substantially the same size and are covered suitably, as with mosquito-netting *q*, and the free edge of frame *p* is provided with clips or fastening devices *r*, which snap over the side bar *f*, whereby the frames *o p* are held in inverted-**V** shape. The outer longitudinal bars of the frames *o p* are preferably beveled off, as indicated. 80 85

The rockers are moved above the stops or abutments *k* when they are out of use. When the parts of the combined cot and crib are folded up, as shown in Fig. 3, they may be 90 tied together by means of the rope or cord *l*.

The invention is susceptible of various apparent modifications which are within the spirit and scope of the invention; but it is clear that some features may be used without 95 others.

Therefore what I claim as new is—

1. A folding cot or crib comprising a flexible bottom, a frame for such bottom supported by cross-bars suitably pivoted to a 100 central cross-bar, and side-bar-reinforcing braces suitably mounted upon the central cross-bar and adapted to support the frame.

2. A folding cot or crib comprising a flexible bottom and a frame supported by braces 105 suitably pivoted to a central cross-bar and reinforcing-braces adapted to enter suitable recesses in the frame and the cross-bar, suit-

able eyes or guides on the supporting parts and a cord or rope led through the eyes or guides to secure the parts in position.

3. A combined cot and crib, comprising 5 suitably-connected legs forming a frame and provided with a bottom, abutments or stops at the sides of some of said legs, rockers each pivoted at one end to one of the remainder of said legs, and a cord or rope, said frame being provided with eyes or guides, and said cord or rope being connected with the rockers and led through said eyes, for substantially the purpose set forth.

4. A combined cot and crib, comprising a 15 folding frame, consisting of a pivot-rod, crossed legs pivoted to each end of the rod, and front and rear side bars connecting the upper ends of the legs, a bottom applied to the side bars, reinforcing-braces adapted to enter recesses in the pivot-rod and side bars and a folding canopy consisting of covered and movably-connected front and back frames, one of said canopy-frames being 25 hinged to one side bar, and the other being

provided with fastening means for engaging 25 the other side bar, substantially as described.

5. A combined cot and crib, comprising a folding frame, consisting of a pivot-rod, crossed legs pivoted to each end of the rod, and front and rear side bars connecting the 30 upper ends of the legs, a bottom applied to the side bars, reinforcing-braces adapted to enter recesses in the pivot-rod and side bars, abutments or stops at the sides of the front legs, rockers each pivoted at the rear end to 35 one of the other of said legs, and means for holding the other ends of the rockers in firm contact with said abutments or stops, substantially as described.

In testimony whereof I have affixed my 40 signature in presence of two witnesses.

ISABELLA VREELAND,
Administratrix of the estate of Anthony W.
O'Blenus, deceased.
